UNITED STATES PATENT OFFICE.

CORNELIUS B. CORCORAN, DECEASED, LATE OF NEW YORK, N. Y.; BY MICHAEL J. CORCORAN, ADMINISTRATOR, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed February 4, 1924. Serial No. 690,418.

To all whom it may concern:

Be it known that CORMELIUS B. CORCORAN, deceased, late a citizen of the United States, and late residing in the borough of Bronx,

5 county of Bronx, city and State of New York, invented certain new and useful Improvements in Typewriting Machines, of which the following is a specification.

This invention relates to a letter-feeding 10 mechanism of typewriting machines, and comprises means for feeding the carriage more than one space in certain instances.

At the end of a sentence it is customary 15 to leave two or more letter-spaces. Devices have been used heretofore whereby a single depression of a space-key will cause the carriage to advance a plurality of letter-spaces.

The present invention provides a mechanism actuated by the period-type-key, to 20 enable the operator to make an extra space after the period.

A multiple-spacing pinion that is mounted 25 on an arm is moved by the period-key into mesh with the feed-rack of the carriage, and lifts the same off from the usual escapement pinion. The carriage, after typing, is thus freed to be advanced by its spring until the multiple-spacing pinion is arrested by a stop. Upon the release of the 30 period-key, the feed-rack re-engages the escapement pinion and the other parts are returned to their original positions. By adjusting said stop, the carriage may be caused to advance any desired number of 35 letter-spaces at the operation of the period-type-key.

Other features and advantages will hereinafter appear.

In the accompanying drawings,

40 Figure 1 is a fragmentary perspective view of an Underwood typewriting machine embodying the present invention.

Figure 2 is a fragmentary detail illustrating 45 the position of the multiple-space pinion when out of engagement with the feed-rack.

Figure 3 is a similar view to Figure 2, but shows the multiple-space pinion in engagement, the rack having been lifted off the escapement pinion and advanced several 50 spaces.

Figure 4 is a plan view, showing a detail of the pinion mounted on the lever which is connected to the period-key.

Figure 5 is a fragmentary side elevation, 55 showing the type-bar with an extended cam-slot and the co-acting parts in printing positions.

Figure 6 is similar to Figure 5, showing the parts in position after the period-key is fully depressed, with the link-stud in the 60 cam-slot acting to retract the type-bar from the platen to prevent a blur.

Key 10, for typing the period-character, is mounted on bar 11 fulcrumed in the usual manner on rod 12. A twisted connecting link 13 extends from bar 11 to one arm of a bell-crank 14, fulcrumed on an upstanding bracket 15 attached to the frame of the machine. A link 16 connects the opposite arm of the bell-crank 14 to another bell-crank 17 having a forked arm 18 in which is mounted a multiple-spacing pinion 19. Pinion 19 is movable with arm 18 to mesh with feed-rack 20 of carriage 21 to lift the 70 rack 20 off a pinion 22 of the escapement 75 mechanism 23. A connecting link 24 is pivotally mounted on a cross-rod 25, connecting the type-bar 26, in this case carrying the period-type-character, with bar 11 by means of link-stud 28 projecting from link 24 to engage slot 29 in bar 11, and type-bar 26 swings about point 27 on the usual 80 segment plate.

When key 10 is depressed, the type-bar 26 is swung rearwardly until the type strikes 85 the platen 30 to print the period, and simultaneously bell-crank 17 raises pinion 19, through the linkage above described, to mesh with and lift rack 20, and in doing so disengages the same partly from the contact 90 with escapement pinion 22. The stud 28 of link 24 has at this time reached what is nominally the end of the slot 29 in type-bar 26, the parts being in the position shown in Figure 5; and, in order to provide for an additional movement necessary to completely disengage carriage 21, slot 29 is extended 95 radially to form a cam-slot 29^a, permitting the stud 28 of link 24 to have further travel 100 therein. The rack 20 is thereafter lifted free from the escapement pinion 22, and the impelling mechanism of carriage 21 advances the latter a number of spaces, as determined by the rotation of the multiple-space pinion 19.

The extent of rotation of pinion 19 is de-

- termined by an adjustable stop in the form of a screw 31, which may be inserted in one of a number of apertures 32 formed in the side of one of the prongs of forked arm 18. 5 This stop 31 is contacted by a co-operating projection or stop 33, secured to pinion 19. A spring 34 normally maintains the pinion 19 in retracted position, holding the projections 33 in engagement with a fixed stop 35 secured on the forked arm 18, best shown in 10 Figure 4. One end of spring 34 may conveniently be attached to the projection 33, and the other end to a stationary screw or pin 36 upon which the pinion 19 rotates. 15 The apertures 32 may be positioned so as to correspond to the letter-spacing movements of carriage 21. Thus, if stop 31 is placed in the first aperture, the depression of the key 10 will cause the period to be typed 20 and the carriage 21 to feed forwardly or be jumped two spaces thereafter; if placed in the second aperture, the carriage will feed forwardly or be jumped three spaces, and so on. The positions of apertures 32 may be 25 chosen so that, on releasing period-key 10, the feed-rack 20 will be in proper position to mesh with the teeth of the escapement pinion 22.
- Key-lever spring 37, which may preferably be made somewhat stronger than regular key-lever springs, will return the pinion 19, type-bar 26 and the other moving interconnecting members to their original positions after the period-key 10 is released.
- 30 Variations may be resorted to within the scope of the invention, and portions of the improvements may be used without others.
- Having thus described the invention, I claim:
- 40 1. In a typewriting machine, the combination of a carriage, letter-feeding mechanism therefor, a type, an element for operating said type and controlling the operation of said letter-feeding mechanism, and selective means for automatically securing a variable 45 number of blank spaces upon the operation of said type, including means controlled by said operating element at the operation of said type, for releasing the carriage from the letter-feeding mechanism and jumping the carriage forwardly a predetermined uniform 50 number of spaces from substantially any position of the carriage in its travel, said means including a part adjustable to determine the number of blank letter-spaces 55 jumped by the carriage.
- 60 2. In a typewriting machine, a type, a type-operating key, a carriage, a feed-rack connected thereto, escapement mechanism including a pinion, means for lifting the rack off the pinion, means controlled by said key for operating said lifting means at the typing operation, a stop brought into use by said key for arresting the carriage after 65 jumping a uniform number of spaces from

substantially any position of the carriage, and adjustable means to determine the number of blank spaces to be jumped by the operation of said key.

3. In a typewriting machine, the combination of a type, a type-operating key, a power-driven carriage having a letter-feed mechanism, a device movable by said carriage but normally disconnected therefrom, and means controlled by said key at the typing operation for connecting said movable device to the carriage and releasing said feeding mechanism, and means adjustable to determine the number of blank letter-spaces said device shall be moved by said carriage.

4. In a typewriting machine, the combination of a type, a type-operating key, a power-driven carriage having a rack, a pinion normally disengaged from said rack, said key having means to connect said pinion with said rack for controlling the feed movement of the carriage, said carriage having a letter-feed mechanism releasable by said key, and means adjustable to determine the number of blank letter-spaces jumped by the carriage while driving said pinion.

5. In a typewriting machine, a carriage, letter-feeding mechanism therefor, an operating element, means for releasing the carriage from the letter-feeding mechanism and jumping the carriage forwardly a uniform number of spaces from substantially any position of the carriage in its travel with one stroke of the operating element, and means actuated by the same stroke of said element to type a character prior to releasing and jumping the carriage, said first means including a part adjustable to determine the number of letter-spaces jumped by the carriage.

6. In a typewriting machine having a platen, in combination, a carriage, a feed-rack connected thereto, escapement mechanism including a pinion, means for lifting the rack off the pinion, a type-bar carrying type, connecting members for lifting said rack and for concomitantly actuating the type-bar to type a character, a key to operate said members, an adjustable stop brought into use by said key for arresting the carriage after jumping a uniform number of spaces from substantially any position of the carriage, and means on one of the members to permit the striking of a type on the platen prior to lifting said rack free from the pinion.

7. In a typewriting machine, the combination of a power-driven carriage having a letter-feeding mechanism, a device movable by said carriage but normally disconnected therefrom, an operating element to concomitantly type a character and connect said movable device to the carriage for releasing said feeding mechanism, means connected with said element to allow releasing of said

feeding mechanism only after completion of the typing operation, and means adjustable to determine the number of letter-spaces said device shall be moved by said carriage.

5. 8. In a typewriting machine, the combination of a type, a type-operating key, a power-driven carriage having a rack, a pinion normally disengaged from said rack, said key having means to connect said 10 pinion with said rack for controlling the letter-feeding movement of the carriage, said carriage having a letter-feed mechanism releasable by said key, and means adjustable to control the number of blank letter-spaces 15 jumped by the carriage while driving said pinion.

9. In a typewriting machine having a platen, in combination, a carriage, a feed-rack connected thereto, escapement mechanism including a pinion, a type-bar carrying type, connecting members for lifting said rack and for concomitantly actuating the type-bar to type a character, a key to operate said members, means operable by said 25 key for lifting the rack off the pinion, an adjustable stop brought into use by said key for arresting the carriage after jumping a uniform number of spaces from substantially any position of the carriage, and 30 means on one of the connecting members to permit the striking of a type on the platen prior to lifting said rack free from the pinion, said means including a part for retracting the type from the platen after 35 printing to prevent blurring a work-piece during the subsequent shifting of the platen.

10. In a typewriting machine, in combination, a carriage, a feed-rack connected thereto, escapement mechanism including a pinion, a type-bar, connecting members, one having a stud moving in a slot in said type-bar for actuating the latter to typing position, and another for simultaneously lifting said rack partly off said escapement pinion, an extension to said slot for allowing further movement of the stud therein to permit the rack to be lifted free from the pinion to release the carriage, a key to operate said members with a single stroke, and 45 an adjustable stop brought into use by said key for arresting the carriage after jumping a uniform number of spaces from substantially any position of the carriage.

11. In a typewriting machine having a platen, in combination, a carriage, a feed-rack connected thereto, escapement mechanism including a pinion, a type-bar carrying type, connecting members, one having a stud moving in a slot in said type-bar for actuating the latter to typing position, and 50 another for simultaneously lifting said rack

partly off said escapement pinion, an extension to said slot for allowing further movement of the stud therein to permit the rack to be lifted free from the pinion to release 65 the carriage, a key to operate said members with a single stroke, and an adjustable stop brought into use by said key for arresting the carriage after jumping a uniform number of spaces from substantially any position of the carriage, said slot-extension being cam-shaped to retract the type-bar from the platen after typing for preventing a blur on a work-piece during the letter-space jumping movement of the carriage. 70

12. In a typewriting machine, in combination, a carriage, a feed-rack connected thereto, escapement mechanism including a pinion, a type-bar, connecting members, one having a stud moving in a slot in said type-bar for actuating the latter to typing position, and another for simultaneously lifting said rack partly off said escapement pinion, an extension to said slot for allowing further movement of the stud therein to permit the rack to be lifted free from the pinion for releasing the carriage, and a key to operate said members with a single stroke. 80

13. In a typewriting machine having a platen, in combination, a carriage, a feed-rack connected thereto, escapement mechanism including a pinion, a type-bar carrying type, connecting members, one having a stud moving in a slot in said type-bar for actuating the latter to typing position, and another for simultaneously lifting said rack partly off said escapement pinion, an extension to said slot for allowing further movement of the stud therein to permit the rack to be lifted free from the pinion for releasing the carriage, and a key to operate said members with a single stroke, said slot-extension being cam-shaped for retracting the type-bar from the platen after typing to prevent blurring a work-piece during the 90 letter-space movement of the carriage. 95

14. In a typewriting machine having a step-by-step letter-space moving carriage, in combination, a platen, a type-bar, a key-lever for operating said type-bar, a member connecting the key lever to the type-bar, said member having a stud thereon moving in a slot in the type-bar for actuating the latter to typing position, and an extension to said slot to permit further movement of the stud therein for retracting the type-bar from the platen after typing to prevent blurring a work-piece during the letter-space movement of the carriage. 110

MICHAEL J. CORCORAN,
Administrator of the Estate of Cornelius B.
Corcoran, Deceased.
